UNITED STATES PATENT OFFICE.

LYMAN H. SNYDER, OF BRISTOL, CONNECTICUT.

DESIGN FOR A HOLDER FOR CURLING-TONGS HEATERS.

SPECIFICATION forming part of Design No. 28,737, dated May 31, 1898.

Application filed April 21, 1898. Serial No. 678,393. Term of patent 7 years.

To all whom it may concern:

Be it known that I, LYMAN H. SNYDER, a citizen of the United States, residing at Bristol, in the county of Hartford and State of Connecticut, have invented and produced a new and original Design for a Holder for Curling-Tongs Heaters, of which the following is a specification, reference being had to the accompanying drawings, in which—

Figure 1 is a plan view of a holder for curling-tongs heaters, showing my new design; and Fig. 2 is a side elevation of the same.

As shown in the drawings, the leading or material feature of my design consists of a ring A, an ornamental band 3 in the top face of said ring, three curved lugs 4 on the under face thereof, two round rods 5 radiating from said ring at two of said lugs, and a third, but longer, round rod 6 radiating from the other

one of said lugs, the latter rod 6 being provided with a handle B. The ring A is flat upon its top or face side, except at the band 3, which is depressed slightly below the face of said ring. The outer and inner edges of said ring are at a right angle to the face thereof, and the three lugs, two of which are shown in Fig. 2, project downwardly below the under side of the body of the ring with a semicylindrical under face.

Having now described my invention, what I claim as new, and desire to secure by Letters Patent, is—

The design for a holder for curling-tongs heaters as herein shown and described.

LYMAN H. SNYDER.
